UNITED STATES PATENT OFFICE.

LEE A. FRAYER, OF COLUMBUS, OHIO, ASSIGNOR TO HIMSELF AS TRUSTEE FOR HIMSELF, WILLIAM E. RANNEY, AND WILLIAM H. BUDD, ALL OF COLUMBUS, OHIO.

MACHINE FOR MAKING NUT BLANKS.

Application filed November 6, 1922. Serial No. 599,273.

To all whom it may concern:

Be it known that I, LEE A. FRAYER, a citizen of the United States, residing at Columbus, in the county of Franklin and State of Ohio, have invented a certain new and useful Improvement in Machines for Making Nut Blanks, of which the following is a specification.

This invention relates more particularly to the type of machine in which the nut blank or other device is drilled and cut from a bar of fed and rotated stock and has for its object to provide an automatic machine improved in sundry respects whereby the various operations are performed with greater speed, economy and accuracy than in machines heretofore proposed. Such machines are commonly termed "bar machines."

The invention is embodied in the mechanism herein shown and described, the features and combinations of features being finally claimed.

In the accompanying drawings—

Figure 1 is a side elevation of the right hand side of the machine.

Fig. 2 is a sectional detail showing the slip joint in the rod for operating the bar feed tube.

Fig. 3 is a top plan view of the machine.

Fig. 4 is an elevation of the forward end of the machine.

Fig. 5 is an elevation of the rear end of the machine.

Fig. 6 is a cross section on the line VI—VI Fig. 3.

Fig. 7 is a cross section on the line VII—VII Fig. 3.

Fig. 8 is a cross section on the line VIII—VIII Fig. 3, showing the tool platens turned out.

Fig. 9 is a horizontal section on the line IX—IX Fig. 1 looking down.

Fig. 10 is a cross section on the line X—X Fig. 3.

Fig. 11 is an edge elevation of one of the platens in inverted position with a tool setting device thereon for setting the tools.

Fig. 12 is a longitudinal sectional view showing the arrangement of the bar feeding, chucking, stopping and drilling means.

Fig. 13 is a front view on a larger scale of the clamping tool holder and means for limiting its movements.

Fig. 14 is an edge view of the same showing in section the frictional moving means 55 for the tool holder.

The particular variety of nut blank manufactured with the machine as herein shown is known as "chamfered washer" the washer being an imitation of one and formed integral with the nut. The form of stock bar, portions of which are shown at 14, is hexagonal in cross section although other forms of bar can be used. The nut blank as cut from the bars is shown at 14^a Fig. 12. 65

The drawing illustrates two units of simultaneously operable mechanisms driven from a single source of power. As the two operating units are alike a description of one will suffice for both. 70

The operating parts are mounted in a main frame 15 composed of parts designed and adapted to receive and sustain the several elements of the invention and the operating mechanism. 75

Referring more particularly to Fig. 12 the character 16 designates the feed tube for the bar stock, said tube having threaded to it at its forward end a removable section 16^a slit to form spring fingers for frictionally 80 engaging the stock bar at its forward end with sufficient firmness to aid the rear gripping means in feeding it forward when the bar is long and to alone feed the bar forward when the bar is so reduced in length 85 as not to be acted on by the rear gripping means. The section 16^a is made removable so that another section suitably different to grip a correspondingly different diameter of stock may be substituted for it. In the 90 present invention the rear end of the tube 16 is provided with what is termed a "ratchet" grip, it consisting of a cage ring 17 having pockets containing balls 18 movable on forwardly and outwardly inclined 95 bottoms of the pockets so that when the tube is moved forward the balls firmly or positively grip the bar, but when the tube is moved rearward they lose their grip. As the rear grip is also made in different sizes 100

to feed stock bars of different diameters the cage is removably attached to the end of the feed tube by means of a retaining ring 19. The feed tube is both rotated and reciprocated, the reciprocating means including a fork lever 20 straddling the feed tube and having its fork arms further forked to engage trunnions on a yoke ring 21 seated in an annular groove on the end 10 of the tube. The ring 21 permits the feed tube to be rotated. The fork arm is oscillated by yielding means, to be hereinafter referred to, a stop 22 being provided to limit the movement of said arm and the feed 15 tube rearward.

The character 23 designates a chuck sleeve which has removably connected with its forward end an externally flared collet 24, the 20 jaws of which are compressible against the bar stock when the sleeve is moved rearwardly and the collet drawn into the correspondingly flared cavity 25^a of the forward end of the work spindle 25. The said work spindle, the chuck sleeve and chuck 25 jaws together with the feed tube are all rotatable together by power from the main shaft 72, suitable bearings at 26 and 26^a being provided. To automatically move and hold the chuck sleeve and jaws axially with 30 reference to the work spindle and for the purpose of compressing the chuck jaws to grip the stock bar I employ centrifugal elements including weights 27 on arms 28 pivoted to large gear 30 and linked to levers 35 29 to toes 29^a of which engage a forwardly facing annular shoulder on the chuck sleeve 23. The weights 27, when thrown outward by centrifugal action cause the chuck sleeve and its jaws to move rearwardly with reference 40 to the work spindle with the effect stated. The parts described are designed to be rotated quite rapidly by means of the aforesaid gear wheel 30 impelled by a pinion 30^a on the main drive shaft 72 as hereinafter set forth.

31 designates the drill, it being removably secured with a taper or other suitable fit in the rear end of a spindle 32. The spindle 32 is feathered to a quill 33 for longitudinal 50 movement therein, said quill carrying a sprocket wheel 34, driven by a belt 34^a from the power shaft 72. The quill is supported to rotate without longitudinal movement in suitable ball bearings in the main frame, 55 while the rear end of the drill spindle is supported in similar bearings in a non-rotative rack sleeve 35 moved back and forth by a feed pinion 36. Said feed pinion, in the instance shown, has variable rocking 60 movement and the rack is made long enough to provide for actuation by the feed pinion at different portions thereof to accommodate different lengths of drill. The drill spindle can be adjusted by means of a hand 65 wheel 36^a suitably geared to slowly operate

pinion 36. The drill spindle is made with an axial bore therethrough to receive a drill-dislodging rod 37, such dislodgment being effected by quick forward movement of the rack carrying the drill spindle by manual 70 operation of the drill feed pinion 36 with its handle 36^b (see Figs. 1 and 3) to cause an impact of the forward end of said rod with the cap 38 fixed on the end of the main frame of the machine to loosen the drill in 75 its socket after which the drill may be easily removed. The drill is alined axially with the fed stock bar and drills the hole that, if the part removed be a nut blank, is to be subsequently threaded. 80

40 designates the body of the drill guide, said guide having removably fixed therein in a suitable bushing 41 through which the drill operates. The body 40 is slidingly mounted in ways 42 on a platen 48 said ways 85 being formed to cause the bushing 41 of the drill guide to move in line with its axis toward and from the end of the stock bar. For this purpose the guide body 40 carries a wormlike stop rack 43 actuated by a worm 90 pinion 44 on a rock shaft 45 lying transversely of the machine and mounted in the platen 48. The stop rack 43 can be adjusted to change the position thereof in relation to its actuating pinion 44 by any 95 means, as for example, a worm accessible through hole 46 to engage a worm pinion 47 on the end of the rack. Said worm can be turned with a wrench applied to its exposed end. Such an adjustment is made to vary 100 the thickness of the nut or other devices to be cut from the stock. The drill guide also functions as a stop in its rearmost position to limit the feed of the stock bar. The recession of the guide on the drill from its bar 105 stopping position and while the latter is working leaves room for the escape of chips made by the drill.

In accordance with my invention I employ two tools for cutting the nut, one tool 110 to cut the chamfer and washer rim and the other tool to sever the nut at the plane of the end of the washer rim. For brevity's sake I shall refer to one tool as the "chamfer" and the other as the "severing" tool. 115 Means are provided for causing said tools to move successively into cutting position—that is to say the severing tool is to follow the completion of the operation of the chamfering tool. Said tools are arranged to work 120 at opposite sides of the bar. The chamfering tool, designated 50, is adjustably secured on the end of a lever 51 fulcrumed on a shaft 52 journaled in a suitable bearing on the platen 48. Said shaft 52 has affixed to it a sector 53 having its rim provided with spiral teeth engaged by a spiral pinion 54 on the rock shaft 45 so that when said shaft is rocked it tends to rock the lever 51; but the shaft 52 is equipped with a cone 55 125 130

slidable on but rotating with the shaft and clutching in a washer or sleeve 56 of friction material (leather for example) set in a conical cavity of the hub of lever 51. The sliding cone 55 is pressed against the washer 56 with a spring tension washer 58 held by a threaded nut 59 on the end of the shaft 52 so that the tension of the bearing can be regulated as may be necessary from time to time. The lever 51 is provided with a lug 51^a affixed thereto said lug oscillating between two adjustable stops 60 and 61 on the platen 48 so that the movement of the chamfering tool is limited in both directions notwithstanding the aforesaid tendency of the spiral pinion 54 acting on the sector gear 53 to carry it beyond those limits. The construction just described may be termed correcting means. The severing tool 20 designated 62 is adjustably secured on the end of a lever 63 fulcrumed on a shaft 64 journaled in a suitable bearing on the platen 48. Said shaft has affixed to it a sector 65 having its rim cut with spiral teeth to form a gear engaged by a spiral pinion 66 on the rock shaft 45 so that when said shaft is rocked it rocks the lever 63 and the severing tool into and out of position to cut the bar. The sector gear and their operating pinions 30 are formed or geared to operate the tools in contrary directions. No means for limiting the movement of the severing tool, except as far as might be incident to the operation of the spiral pinion 66, are necessary or shown, first, because the tool is set in its holder in proper relation to the chamfering tool to follow the cut of that tool, and second, because the severing tool is intended to cut through the bar to the region of the drill 40 cut to separate the nut blank from the bar. The platen is hinged at 48^a to the side of the main frame and by removing the crank or the connection thereof can be turned out into inverted and exposed position, as shown in Fig. 8, to permit the convenient affixing, adjustment, or removal of the tools.

The power for driving or operating the mechanism is conveniently derived from an electric motor 70 installed on top of the main frame at the forward end thereof. From the power shaft is extended a belt 71 common to the two main drive shafts 72, 72 (see Fig. 3). Mounted on a shaft 73 extending between the sides of the main frame is a cam drum 90 having in one face the drill and cut off cam groove 74 and in the opposite face the bar feed cam groove 75. Also on said shaft 73 is the chuck operating cam 76 and a large worm gear 77 operated by a worm pinion 78 on a shaft 94 the latter taking power through an intermediate gear 79 from the main drive shaft 72. The shaft 72 is provided with a suitable friction clutch 95 operated by lever 95^a at the forward end of the machine. The stock

bar feed fork lever 20 is operated by the cam groove 75 through a bell crank 80, rods 81 and 82, connected with a crank arm 20^a on the shaft of the fork. Between the rods 81 and 82 is an adjustable frictional slip 70 joint 81^a with compressible washers so that the forward movement of the stock bar is limited by its contact with the drill guide rather than by the full stroke of the rod 81. This is termed a corrective means. It will 75 be remembered that the rearward stroke of the fork 20 is limited and corrected by the stop 22. The chuck collet is released from the bar and against the pressure of the centrifugal weight by the cam 76 acting on crank arm 83^a through rod 83 and a crank arm 86 on a rock shaft 87 carrying a pivoted yoke 88 engaging trunnions 88^a on a bearing ring 89, these parts being connected with the rear portion of the chuck sleeve. 80 The transverse rock shaft 45 is rocked from cam groove 74 through rod 84 and suitable lever 84^a and crank connections. The drill feed is also operated from cam groove 74 by means of rod 85 and a suitable lever 85^a 90 and crank connections. The several connections can be made adjustable, as shown, to vary the extent of the oscillations or reciprocations of the parts so operated as may be desirable. 95

To apply the feed each of the shafts 94 is provided with an ordinary or suitable friction clutch 91 operated by lever 92 at the front of the machine and either unit can be operated independently of the other or 100 both can be operated simultaneously.

Suitable pumps 96 operated by belts 97 from the shaft 72 can be provided for circulating cooling liquid around the cutting tools, suitable conduits and passages being 105 provided for such liquids.

In the construction shown and described it will be noted that stock and drill are turned in opposite directions.

As it is important that the tools be accurately set before commencing the operation of the machine a block 67 of triangular prismatic form can be temporarily substituted for the drill guide in the platen 48 (see Fig. 11) the apex of said block serving 110 as the guide for locating the cutting edges of the tools in proper cutting relation to each other.

To prepare the end of the bar for the removal of nut blanks the stock is inserted 115 while the feed is in open position and the chuck in released position the stock being inserted sufficiently to permit trimming the end of the bar by the chamfer and severing tools. Power is then applied by the clutch 120 to the main shaft 72 and the feed applied on shaft 94. The parts of the mechanism are so timed that the following operations ensue. As the severing tool recedes from 125 its innermost position by virtue of the 130

movement of the shaft 45 the chamfer tool likewise recedes and the stock stop moves toward the on-coming stock. Simultaneously with this action the drill moves to the 5 forward limit and the chuck jaws are moved so that by the time the severing tool is clear of the oncoming stock the chuck is open and the feed fingers operate to move the stock bar forward. The stock then 10 abuts against the stop and the chuck is rapidly closed by the action of the centrifugal weights the cam 76 being so formed as to permit this. The drill then moves rearward to cut and at or about the same time 15 the chamfering tool also begins to cut both continuing to cut, the chamfering tool completing its work while the drill continues to operate. After the chamfering tool completes its work the severing tool begins to 20 cut and continues to cut until a very small wall is left between it and the cavity made by the drill at which time the drill ceases to cut and rapidly withdraws, the severing tool finishing its work shortly before the 25 drill has entirely withdrawn from the bar. While the chamfering tool and drill are working the stock stop begins its recession. At the completion of the cut-off the severing tool moves outwardly, the stop rearwardly and the drill forwardly thus forcibly stripping the finished blank from the 30 end of the drill. When the severing tool has moved to clearance position the chuck by the action of the cam 76 opens and the 35 described cycle of operations repeated.

The nut blanks, as fast as cut, along with the chips escape down a chute and the grating 98, the nuts being screened or separated from the chips by the grating.

40 The forms of the parts can be changed without departing from the gist of the invention as claimed.

What I claim is:

1. In a machine for cutting portions from 45 a bar of stock, the combination of means for intermittently feeding the stock, a drill, a drill guide and means for moving the drill guide axially with reference to the drill, and means for severing a portion from the 50 bar.

2. In a machine for cutting portions from a bar of stock, the combination of means for intermittently feeding the stock, a drill, a drill guide and means for moving the drill guide axially with reference to the drill 55 during the cutting operation of the drill on the stock and means for severing a portion from the bar.

3. In a machine for cutting portions from 60 a bar of stock, the combination of means for intermittently feeding the stock, a drill, a drill guide and means for reciprocating the drill guide axially with reference to the drill, and means for severing a portion from 65 the bar.

4. In a machine for cutting portions from a bar of stock, the combination of means for intermittently feeding the stock, a drill, a drill guide and bar stop, and means for moving said drill guide and bar stop axially 70 with reference to the drill, and means for severing a portion from the bar.

5. In an automatic bar machine, the combination of a stock chucking means, a stock 75 feeding member consisting of a friction member and a reciprocating frictional operating member.

6. In an automatic bar machine, the combination of a stock chucking means, a stock 80 feeding member consisting of a friction portion and a positively gripping portion, a reciprocating frictional operating member and a correcting member for the stock feeding member.

7. In an automatic bar machine, the combination of a stock chucking member, a stock 85 feeding member consisting of a frictional portion and a ratchet portion, a frictional operating means for said feeding member and a correcting means for the latter. 90

8. In an automatic bar machine, the combination of a stock chucking mechanism, a stock 95 feeding member consisting of a frictional portion, a ratchet portion, a frictional operating means for said feeding member, a drilling mechanism, a chamfering means, a cut off means, a stock stopping device and an axially moving drill guide.

9. In an automatic bar machine, the combination of a stock chucking means, a stock 100 feeding means, a stock stopping means, a drilling means, a drill guiding means, a cut off means and a frictionally controlled chamfering means.

10. In an automatic bar machine, the combination of a stock chucking means, a stock 105 feed, a stock stopping means, a drilling means, a drill guiding means, a cut-off means, a frictionally controlled chamfering means and correcting means therefor. 110

11. In an automatic bar machine, the combination of a centrifugally closed stock chucking means, a stock feeding means consisting of a friction portion and a ratchetable portion, frictional operating means therefor, an axially operated stock stopping mechanism, a drilling means, an axially operated drill guide, a cut off means, a frictionally operated chamfering means and stopping and correcting means therefor. 115 120

12. In an automatic bar machine, the combination of a friction driven chamfering tool with correcting means therefor, a severing tool and a single cam for causing the severing tool to operate subsequent to the 125 operation of the chamfering tool.

13. In an automatic bar machine, the combination of a main frame, a platen hinged thereto, a chamfering tool and a severing tool mounted on said platen, a rock shaft 130

in said platen for operating said tools, and detachable means for the application of 10 power to said rock shaft.

14. In an automatic bar machine, the combination of a main frame, a platen hinged thereto, said platen adapted to receive tool setting means, a chamfering tool and a severing tool mounted on said platen, a rock shaft 15 in said platen for operating said tools, and

detachable means for the application of 10 power to said rock shaft.

15. In an automatic bar machine, the combination of a main frame, a platen hinged thereto, a cutting tool mounted thereon, and means for the application of operating 15 power to said tool.

LEE A. FRAYER.
